Application April 17, 1937, Serial No. 137,468

27 Claims. (Cl. 197—11)

This invention relates generally to improvements in printing machines and more specifically to an electrically operated typewriter controlled by a combination key stenographic key-board.

It is an object of the present invention to provide a typing machine with less than the usual number of keys and yet wherein it is possible to print in one stroke, words of four or five letters. Direct stenographic recording is thus made possible at high speeds.

Another object of the invention is the provision of a key arrangement making it possible to represent four and five letter words with a simultaneous operation of the digits of the two hands. A feature of this invention is the arrangement of special control keys for operation along with the letter keys by the same digits to select the capital shift, shift lock, space, back space, tabulate, and carriage return controls.

Another object of the invention is the provision of an improved permutational arrangement of keys involving the use of two fingers in cooperation with six keys to depress thirty-five different combinations of the keys, each combination representing a letter, numeral or special character. Heretofore, in the art, it was shown that the fingers and thumb of a hand may cooperate with five keys to depress them singly or in combination to record one of a plurality of characters. That system has its limitations, however, because even when two hands are used, no more than two characters may be set up at a time. In the present case, two similar fingers of both hands are worked in combination with six keys, three of which are associated with each finger. For example, both index fingers cooperate in the making of a permutational setup of one or more of six keys. Thus, by the use of the five pairs of fingers and thumbs it is possible to set up five character combinations simultaneously where heretofore only two combinations were possible.

An object of the invention is the provision of electrical contact devices operated by a set of keys depressed by fingers of both hands for selecting the printing of one of a plurality of characters greater in number than the number of keys. One of thirty-five characters may be selected by six keys arranged in two columns of three keys which are operated singly or in pairs by similar fingers of both hands. Four or five of such sets of six keys may be operated at once to control the typing of a group of letters comprising a word.

A feature of the invention is the distally controlled sequence of character representation. The stronger pairs of inner digits, the thumbs and index fingers, serve to select frequent short words and first letters of all other words while the outer fingers only come into play on longer words. The sequence of letter representation is in the following order: the thumbs, the index fingers, the middle fingers, the ring fingers, and the small fingers.

An object of the invention is the provision of typewriter timing devices adapted to be controlled distally by the setting of the keys. The sequence of operation of the related pairs of key groups is from the center of the keyboard out to the right and left. For example, the two index fingers control the selection of the first letter of a word, the two middle fingers select the second letter, the two ring fingers pick out the third letter and the two small fingers select the fourth letter.

An object of the invention is the provision of a type bar operating timer that is released only by keys associated with certain fingers. The timer controls the sequence of operation of the typewriter to print selected letters from left to right across a record sheet. The sets of keys associated with the middle and ring fingers call in the timer for operation when more than one letter is to be typed, but when only the index fingers are depressed to select one letter, the timer is not released.

An object of the invention is the provision of a clutch between the timer and a driving motor for the timer. The clutch is connected only when a plurality of letters are to be printed.

Another feature of the present invention is the provision of means for locking the keys in a depressed position and a device for disabling said locking means when the operating switch is in the "off" position. This is done to prevent instantaneous printing when the switch is thrown on, due to keys being depressed and locked down while the machine current is shut off.

Another object of the invention is the provision of means to enlarge the character representing capacity of a printing device controlled by combinations of keys. It is made possible to print a certain character under control of a certain combination of keys depressed by one pair of fingers, and then print another character under control of the same combination of other keys depressed by another pair of fingers.

Another object of the invention is the provision of an improved form of clutch between a

driving means and a contact timing device for controlling the sequence of letter printing. The clutch is released by an escapement which requires both the depression and restoration of control keys before the clutch is restored in preparation for another cycle. The arrangement is provided in order to prevent repeated printing when keys are held down after printing is accomplished.

10 A further object of the invention is the provision of devices for printing more frequently occurring characters under control of key combinations that are fingered with relatively greater ease in a typewriter controlled by a combination key keyboard.

15 The foregoing objects and other features of the invention will become more apparent as this disclosure continues with reference to the drawings which accompany and form part of this specification.

In the drawings:

20 Fig. 1 shows an arrangement of keys for controlling the recording of five characters simultaneously by the use of the fingers and thumbs 25 of both hands. A pair of control bars are placed near the index finger keys and operable by the index fingers to select special characters.

25 Fig. 2 illustrates an arrangement of keys somewhat similar to that in Fig. 1, but with the further provision of a capital selection bar between 30 the thumb keys.

30 Fig. 3 discloses an arrangement of keys differing from the arrangements in Figs. 1 and 2 in the provision of a space bar to the right of the thumb keys and placement of a capital selection bar at the left of the thumb keys.

35 Fig. 4 reveals a simplified arrangement of keys for controlling the selection of four characters simultaneously using only the fingers and reserving 40 the thumbs for operation of shift, shift lock and space bars.

40 Fig. 5 shows an arrangement of keys like that of Fig. 4 with the addition of back space, tabulate and carriage return control bars positioned 45 for operation by the thumbs.

Fig. 6 is a sectional elevation view of a remote 50 control stenographic keyboard and timer device for operating a typewriter.

Fig. 7 is a plan view of the device shown in 55 Fig. 6.

Fig. 8 is an elevation view of a stenographic 60 keyboard and timer built within the cover of a typewriter.

Fig. 9 is a sectional elevation view of the timer 65 clutch.

Fig. 10 is a detail view of the clutch engaging plate.

Fig. 11 is an end view of the timer clutch.

Fig. 12 is a section of the clutch showing the 60 engaging rollers and slots.

Fig. 13 is an elevation view of a column of keys 65 cooperating with key locking and timer releasing links.

Fig. 14 is a wiring diagram of the machine.

The keyboard arrangements disclosed in Figs. 1-5 are described hereinafter with an explanation of the key combinations and character selections, especially of the combinations of keys 70 in Fig. 5 which is the modification illustrated herein in connection with a typewriter of the kind known as "Electromatic."

The five keyboards illustrated have certain features that are common to all of them. For 75 example, each one comprises three groups of keys,

a left group of keys adapted to be operated by the four fingers of the left hand, a center group of keys which are to be operated by the two thumbs, and a right group of keys designed to be depressed by the fingers of the right hand. Three keys are provided for each finger, the finger tip being normally poised above the center key but a short forward movement brings it over the edges of both upper keys and a further forward movement brings it over the upper key; a short rearward movement positions the finger tip over the two lower keys and another rearward increment of movement serves to select the lower key alone. The keys are positioned to coincide with the natural placement of the finger tips and thumbs of outstretched hands, all finger tips and thumbs normally resting over the center keys of the vertically arranged sets of three keys. A character selection is made by the actuation of two similar digits of the two hands in cooperation with six keys. For example, in Fig. 1 the left thumb cooperates with keys *a*, *b*, and *c*, and the right thumb cooperates with keys *1*, *2*, and *3* to select the first letter of a word. The second letter of a word may be selected by the 10 permutations of keys *d*, *e*, *f*, *4*, *5*, and *6* by the two index fingers. And the fifth letter 15 of a word is selected by the depression of one or more keys *m*, *n*, *o*, *13*, *14*, and *15* by the small fingers of both hands. From the foregoing it is 20 obvious that the sequence of character selection 25 is fingered distally, that is, from the center of the keyboard out towards the sides, the pairs of sets of keys nearest the center selecting the first letter of a word and the two end sets of keys selecting the fifth letter of a word. Thus, in selecting keys to represent the word "black," the two thumbs would select *B*, the two index fingers *L*, the two middle fingers *A*, the two ring fingers *C* and the two small fingers *K*. Through 30 the cooperation of two fingers with six keys to 35 depress various combinations or permutations of one, two, three or four keys, different settings may be made and related to letter, numeral, punctuation mark and special character representation.

In the keyboard illustrated in Fig. 1, the six keys *a*, *b*, *c*, *1*, *2*, and *3* operated by the thumbs 40 may be studied with regard to the various combinations of keys which may be set. An assignment of characters to depressed key combinations 45 may be made as follows:

Character selections	Key combinations	Character selections	Key combinations
<i>A</i>	1	<i>N</i>	3-a
<i>B</i>	1-a	<i>O</i>	3-a, b
<i>C</i>	1-a, b	<i>P</i>	3-b
<i>D</i>	1-b	<i>Q</i>	3-b, c
<i>E</i>	1-b, c	<i>R</i>	3-c
<i>F</i>	1-c	<i>S</i>	1, 2
<i>G</i>	2	<i>T</i>	1, 2-a
<i>H</i>	2-a	<i>U</i>	1, 2-a, b
<i>I</i>	2-a, b	<i>V</i>	1, 2-b
<i>J</i>	2-b	<i>W</i>	1, 2-b, c
<i>K</i>	2-b, c	<i>X</i>	1, 2-c
<i>L</i>	2-c	<i>Y</i>	2, 3
<i>M</i>	3	<i>Z</i>	2, 3-a
		Space	2, 3-b
		Comma	2, 3-b, c
		Period	2, 3-c
		Dash	2, 3-c

70 From the foregoing it is apparent that thirty different combinations of depressed keys may be chosen by the two thumbs cooperating with six keys. In a similar way the other finger key 75

groups may have control to select corresponding characters.

- 5 Keys **d, e, f, 4, 5 and 6** being operated by the two index fingers
  - 5 Keys **g, h, i, 7, 8 and 9** being operated by the two middle fingers
  - 10 Keys **j, k, l, 10, 11 and 12** being operated by the two ring fingers
  - 10 Keys **m, n, o, 13, 14 and 15** being operated by the two small fingers

The numbered keys are operated by the fingers of the right hand, the lettered keys are depressed with the left hand. Each vertical row of three keys on the right side is operated in combination with the corresponding vertical row of keys on the left side. Therefore, the five sets of six keys control the selection of five sets of thirty characters each, totaling one hundred and fifty characters.

Two special bars S1 and S2 are provided to select infrequently used characters. These bars are placed alongside the keys operated by the index fingers and are operated therewith to select special characters.

An assignment of thirty special characters and control operations may be made as follows:

Character and operation selections	Key combinations	Character and operation selections	Key combinations
1	S1, 4	7	S1, 5
2	S1, 4-S2, <i>d</i>	8	S1, 5-S2, <i>d</i>
3	S1, 4-S2, <i>d, e</i>	9	S1, 5-S2, <i>d, e</i>
4	S1, 4-S2, <i>e</i>	0	S1, 5-S2, <i>e</i>
5	S1, 4-S2, <i>e, f</i>	Back space	S1, 5-S2, <i>e, f</i>
6	S1, 4-S2, <i>f</i>	Carriage return	S1, 5-S2, <i>f</i>
Tabulate	S1, 6	Exclamation	S1, 4, 5-S2, <i>e</i>
Comma	S1, 6-S2, <i>d</i>	Colon	S1, 4, 5-S2, <i>e, f</i>
Period	S1, 6-S2, <i>d, e</i>	Beginning parenthesis	S1, 4, 5-S2, <i>f</i>
Dash	S1, 6-S2, <i>e</i>	Ending parenthesis	S1, 5, 6
Quotation marks	S1, 6-S2, <i>e, f</i>	Dollar sign	S1, 5, 6-S2, <i>d</i>
Apostrophe	S1, 6-S2, <i>f</i>	And sign (&)	S1, 5, 6-S2, <i>d, e</i>
Underline	S1, 4, 5	Shilling mark (/)	S1, 5, 6-S2, <i>e</i>
Semicolon	S1, 4, 5-S2, <i>d</i>	Per cent (%)	S1, 5, 6-S2, <i>e, f</i>
Question mark	S1, 4, 5-S2, <i>d, e</i>	Asterisk (*)	S1, 5, 6-S2, <i>f</i>

The fingers of the right hand are normally positioned on keys 2, 5, 8, 11, and 14 and the "rest" positions for the digits of the left hand are over keys b, e, h, k and n.

Words are represented exactly as they are spelled in groups of five letters or less, or by syllable, the order of letter sequence from left to right being selected by the fingers of the right hand from left to right.

Fig. 2 shows an improved key arrangement involving the provision of a capital selection bar 16 between the vertical rows of thumb keys. Since all sentences start with a capital letter, the first letter of a word is frequently capitalized. In order to readily provide for this, the "caps" bar 16 is placed between the keys operated by the thumbs. Since the first letter of a word is selected by these keys, depression of bar 16 by either thumb will capitalize said first letter so that no additional operation is necessary for capitalizing at the beginning of a sentence. This method of capital selection may also be used for the capitalization of proper names, places, dates, etc., wherever the first letter of a word is to be capitalized.

In all other respects the keyboard of Fig. 2 is the same as the keyboard described with reference to Fig. 1. Both are designed with the intention of representing five letters of a word simultaneously in a single downward stroke of the fingers. If more than five letters are included in a particular word, it then would have

to be recorded in two strokes. If there are more than ten letters in a word, three strokes are required, etc., in multiples of five letter groups. Since a large proportion of words comprise five letters or less from the standpoint of frequency of use, and since a great majority of words are ten letters or less, it is obvious that this method of representing words in five letter groups lends itself to a very rapid recording operation making it possible to take dictation and type a direct copy thereof.

The key tops may be blank or provided with characters such as the reference numerals shown to aid in remembering the key combinations or for practice and training purposes. 15

In Fig. 3, there is disclosed a key arrangement very much the same as the arrangements in Figs. 1 and 2, but differing therefrom in the provision of a space bar 17 at the right of the thumb keys, and differing in the rearrangement of the "caps" bar 16' to the left of the thumb keys instead of between them. The space bar 17 may be operated by the right thumb along with the depression of one or two of the keys 1'', 2'', and 3'' or it may be operated alone. Then too, the keys may be operated without operating the space bar 20 25

when the letters set up are merely part of a long word.

The capital selection bar 16' is positioned to be operated by the left thumb. It may be depressed along with one or two of the keys a'', b'', and c'', or depressed alone while the right thumb is depressing a combination of the keys 1'', 2'', and 3''. Keys a'', b'', and c'' may be operated independently of bar 16' when a word is not capitalized or when the setting is made for the second or third part of a long word.

This improved arrangement involving a space bar adds to the capacity of the keyboard in adapting it to select five letters and a space simultaneously. The other two arrangements in Figs. 1 and 2 are limited to four letters and a space in one stroke.

A further advantage in the construction of Fig. 3 lies in the fact that the extra space bar 17 frees each of the five sets of keys from the necessity of providing a combination to select space control. The combinations of keys 2", 3"—a", 55
4", etc., may be used for another character or control selection. Furthermore, the space selection control is concentrated in one bar instead of depending for operation on any one of five sets of keys. 60

The key arrangements shown in Figs. 4 and 5 are like the previously described arrangements in the broad aspect but differ considerably in many ways. They are similar in retaining the idea of using six keys in two sets of three keys

- operable in combinations by the two similar fingers of a pair of hands. But the arrangements of Figs. 4 and 5 differ from the design of Figs. 1, 2, and 3 in the use of a smaller number of character selection keys, only four instead of five characters being selected at one time. This is so because the thumbs are used for control selection only, rather than character selection. Another difference is in the rearrangement of key combinations with respect to letter selection along more scientific lines as a result of a study of letter occurrence in words combined with an observance of comparative finger dexterity. A further difference is in the attainment of a larger number of character selections in all four fingers positions and a full set of shift capitals and characters in all positions rather than in only the thumb and index finger positions as previously. The differences mentioned hereinbefore and the desirable key arrangements in Figs. 4 and 5 resulting therefrom are the product of a line of reasoning and logical conclusions flowing therefrom in a manner about to be described.

Before turning from the five-letter system as shown in Fig. 3 to the four-letter system disclosed in Fig. 4, it is well to show how the comparative speeds of the two systems may be figured and also disclose why useful speeds may be attained on both keyboards because it is possible to execute a number of strokes per second productive of fast word representation.

The computation of the average number of strokes per word is based on the study made by Mr. Godfrey Dewey at Harvard University and published in his book "Relative Frequency of English Speech Sounds." This study determines the words used most frequently in written and spoken English text and constitutes approximately 80% of English from the standpoint of use.

The following table shows the frequency with which words of varying length occur including words having only one letter and those up to fourteen letters in length:

		Word length (number of letters)	Frequency of use
50	1	3,275	
	2	19,088	
	3	22,685	
	4	15,608	
	5	8,125	
	6	3,984	
	7	2,849	
	8	1,467	
	9	952	
55	10	394	
	11	139	
	12	78	
	13	39	
	14		

On the five-letter keyboard words up to five letters may be written in one stroke, words up to and including ten letters require two strokes, and words up to and including fourteen letters require three strokes. Adding the frequencies of these three groups we find the following:

		1 stroke	2 strokes	3 strokes
70		3,275	3,984	139
		19,088	2,849	78
		22,685	1,467	23
		15,608	952	39
		8,125	394	
		68,781	9,646	279

With the four-letter keyboard words up to and including four letters in length can be written in one stroke, words up to eight letters in length require two strokes, words up to twelve letters in length require three strokes and words up to fourteen letters in length require four strokes. Adding the frequencies with which such words occur in the same manner as before we have:

1 stroke	2 strokes	3 strokes	4 strokes
3,275	8,125	952	23
19,088	3,984	384	39
22,685	2,849	139	
15,608	1,467	78	
60,656	16,425	1,563	62

In order to find the average number of strokes per word for the two keyboards the "weighted arithmetic average" for both may be computed according to the "Principles & Methods of Statistics" by Chaddock; see pages 90-93.

The following table shows the computation for determining the average strokes per word for the five-letter keyboard:

Five-letter keyboard

X	W	XW
1	68,781	68,781
2	9,646	19,292
3	279	837
	78,706	88,910

$$M = \frac{XW}{W} = \frac{88,910}{78,706} = 1.129647$$

or 1.13 strokes per word.

In the same manner the average strokes per word for the four-letter keyboard may be computed:

Four-letter keyboard

X	W	XW
1	60,656	60,656
2	16,425	32,850
3	1,563	4,689
4	62	248
	78,706	98,443

$$M = \frac{XW}{W} = \frac{98,443}{78,706} = 1.2507686$$

or 1.25 strokes per word.

The maximum potential speeds of the two keyboards may be estimated by using figures obtained from actual tests with combination key stenograph keyboards of a design not as advanced as the designs set forth in this application. In 1882 Mr. Bartholomew ran tests on a combination key stenographic machine and found that a number of expert operators could perform combinational fingering at the rate of from 760 to 795 strokes per minute. 780 strokes per minute equals 13 strokes per second. Dividing the strokes possible per minute by the average strokes per word

for the two keyboards will reveal the potential maximum speed for each keyboard.

The five-letter keyboard

5 760 to 795 strokes per minute
1.13 strokes per word

673 to 704 words per minute

10 *The four-letter keyboard*

760 to 795 strokes per minute
1.25 strokes per word

15 608 to 636 words per minute

The word writing speeds which we need are about 100 words per minute for personal use, 150 words per minute for business use and 300 words per minute for the fastest and most exacting court reporting work. From the foregoing computations, it is apparent that both keyboard arrangements are adapted for fast operation such as writing directly from dictation.

25 The four-letter keyboard as in Fig. 4 not only is fast enough for all purposes but also involves advantages over the other forms. On this keyboard it is clear that the thumbs are not used for representing characters, but serve only to se-

30 lect the three control operations: shift lock, space and shift. Since the thumbs are not as dexterous as the fingers of the hand, it is desirable to make their work more simple than that of the fingers. With the operations of the thumbs simplified, an increase in the ease of learning how to operate the keyboard may be expected as well as an increase in speed and ease of opera-

35 tation.

In order to devise a combination key arrangement that may be operated at the highest average speed, it is first necessary to determine the relative ease of the 35 fingering combinations possible with six keys operated by two fingers, and then assign the most frequent operations to the 45 key combinations easiest to perform. In setting up the series of fingering combinations, certain basic assumptions are made in the order set forth as follows:

50 1. That the use of one hand is easier than the use of both hands.

2. That the right hand in general is more dexterous than the left.

55 3. That keys beneath fingers in their "rest" positions are more easy to operate than keys where the fingers have to be moved away from their "rest" positions.

4. That a short movement of the fingers away from their "rest" positions is easier than a greater distance of movement.

60 5. That it is easier (very slightly) for the operator to move his fingers away from than toward him.

It is also assumed that in Fig. 4 the fingers 65 normally rest on keys 22, 25, 28, 31, 2b, 2e, 2h, and 2k and the thumbs rest on the space bar 17.

The keys 21, 22, 23, 2a, 2b, and 2c, Fig. 4, may be taken as a typical set of six keys operable by two fingers. The foregoing assumptions, plus 70 experience gained in experimenting with fingering combinations, result in the following arrangement of a series of fingering combinations in order of relative difficulty, No. 1 being the easiest combination to finger, and No. 35, the most difficult:

Relative ease	Key combinations	Relative ease	Key combinations
1.	2b	18.	21
2.	22	19.	23
3.	22-2b	20.	22-2a
4.	2a, 2b	21.	22-2c
5.	2b, 2c	22.	21-2b
6.	21, 22	23.	23-2b
7.	22, 23	24.	21, 22-2a
8.	22-2a, 2b	25.	21, 22-2c
9.	22-2b, 2c	26.	22, 23-2a
10.	21, 22-2b	27.	22, 23-2c
11.	22, 23-2b	28.	21-2a, 2b
12.	21, 22-2a, 2b	29.	23-2a, 2b
13.	22, 23-2b, 2c	30.	21-2b, 2c
14.	21, 22-2b, 2c	31.	23-2b, 2c
15.	22, 23-2a, 2b	32.	21-2a
16.	2a	33.	23-2c
17.	2c	34.	21-2c
		35.	23-2a

The relative frequency of letters, punctuation and keyboard operations per 100,000 words may now be combined with the foregoing sequence of key combinations.

20 It is noted hereinafter that the space operation is the most frequent. This is because there is a space after every word and two spaces between sentences; 100,000 word spaces plus 5,446 sentence spaces, equals 105,446 spaces.

25 The capitalizing of a first letter may be computed as to frequency by adding:

Beginnings of sentences	5,446	30
Proper names	6,404	
An equal number of Mr., Mrs., first and middle names and one or two initials	6,404	
		18,254 35

Lower case letter frequencies and punctuation frequencies per 100,000 words with related key combination selections on keyboard of Fig. 4

Operation	Lower case frequency	Keys depressed
Space	105,446	Space bar 17'
e	36,313	2b
t	31,623	22
a	25,304	22-2b
o	23,576	2a, 2b
h	21,780	2b, 2c
n	19,788	21, 22
i	19,323	22, 23
Capitaliz 1st letter	18,264	1st cap. bar 33
s	15,218	22-2a, 2b

70 It is noted in the foregoing table that the nine most frequent punctuation marks are assigned to key combinations along with the lower case letters. Punctuation marks are nearly always written one at a time, so the nine most frequent marks may be written in the first letter position by the two index fingers, while the remaining 75

eight special characters are to be written in the second letter position by the two middle fingers as explained hereinafter.

It is to be understood that the letter selections pointed out with reference to the index finger keys 21, 22, 23, 2a, 2b, and 2c are also possible with the same relative sequence of fingering on the other three sets of six keys each associated with the middle, ring, and small fingers. For example, the letter s may be represented by keys 25-2d and 2e; f may be written by keys 27, 28, 2g and 2h; and m may be selected by keys 31, 32, 2j and 2k.

When operated with the shift bar 34, the combinations of keys are designed to select upper case characters comprising capitals and numerals. The frequency with which capital letters and numerals occur in written and spoken English text is not taken into account, because it is far more desirable that the key combinations for capitals be the same as for lower case letters rather than the capitals be in order of frequency. Since the capital O and the zero are of the same form, it is possible to include the other nine numeral digits on the same shift as the capitals, the 26 capital letters and 9 numerals totaling 35 characters which is just the selective capacity of one bank of the keyboard. Thus, in the keyboard of Fig. 4, each pair of fingers may select a numeral so that four numerals may be represented with one stroke which is a distinct advantage over the manner of representing single numbers written one at a time with the keyboards in Figs. 1-3.

The key combinations for selecting the capital letters and numerals are noted in the following table:

Capital and numeral representation with related key combination selections on keyboard of Fig. 4

	Operation	Keys depressed
45 E	Shift and 2b	
T	Shift and 22	
O	Shift and 22-2b	
A	Shift and 2a, 2b	
H	Shift and 2b, 2c	
N	Shift and 21, 22	
L	Shift and 22, 23	
S	Shift and 22-2a, 2b	
R	Shift and 22-2b, 2c	
D	Shift and 21, 22-2b	
L	Shift and 22, 23-2b	
F	Shift and 21, 22-2a, 2b	
W	Shift and 22, 23-2b, 2c	
U	Shift and 21, 22-2b, 2c	
M	Shift and 22, 23-2a, 2b	
Y	Shift and 2a	
50 I	Shift and 2c	
2	Shift and 21	
C	Shift and 23	
B	Shift and 22-2a	
G	Shift and 22-2c	
P	Shift and 21-2b	
V	Shift and 23-2b	
60 3	Shift and 21, 22-2a	
4	Shift and 21, 22-2c	
K	Shift and 22, 23-2a	
5	Shift and 22, 23-2c	
6	Shift and 21-2a, 2b	
7	Shift and 23-2a, 2b	
8	Shift and 21-2b, 2c	
9	Shift and 23-2b, 2c	
65 X	Shift and 21-2a	
J	Shift and 23-2c	
Q	Shift and 21-2c	
Z	Shift and 23-2a	

As explained hereinbefore, certain infrequent punctuation marks and special signs may be represented under control of the keys depressed by the middle fingers. They are selected by key combinations similar to the combinations used by the index fingers to select frequent punctuation marks. The special selections are as follows:

Infrequent punctuation marks and special signs and related key combination selections on keyboard of Fig. 4

Operation	Frequency	Keys depressed
Colon.....	218	2j
Beginning parenthesis.....	122	24
Ending parenthesis.....	122	24, 25-2d
Dollar sign.....	76	24, 25-2f
And sign (&.....	23	25, 26-2f
Shilling mark (/.....	16	24-2d, 2e
Per cent (%).....	13	26-2d, 2e
Asterisk (*).....		24-2e, 2f
Any other character.....		26-2e, 2f

Since the infrequent punctuation marks are in the second letter position, the back space key should be depressed before such a representation is made by the combination keys.

In Fig. 4 the "rest" position of the thumbs is above space bar 17' because it is operated frequently as noted before. The left thumb may be moved to the left to cooperate with both bar 17' and a 1st "cap" bar 33 when a first word or a single capital or numeral is to be selected with a space. For long first words, the left thumb is moved further to the left to operate only bar 33 for the capitalization of the first part of a first word. The right thumb may be moved to the left to cooperate with both bar 17' and shift bar 34 when it is desired to represent a series of capital letters or numerals followed by a space. For the first portion of a long series of capitals or numerals, the right thumb is moved further to the right to depress only bar 34 to shift without a space.

The keyboard illustrated in Fig. 5 is similar to that shown in Fig. 4 in all respects except for the provision of three extra controls for operation by the thumbs. These three controls, back space, carriage return, and tabulate, are ordinarily scattered in location on the ordinary typewriter, but in the present design they are grouped close to the other thumb bars. A rearward movement of either thumb away from the space bar 17'' places it over a carriage return bar 36 which may be depressed along with the space bar or alone. A left oblique movement of the left thumb to the rear places it over the back space control bar 35. And a right oblique movement of the right thumb towards the rear places it over the tabulating control bar 37.

From the foregoing portion of the description it is apparent that 30 keys and bars arranged as shown in Fig. 5 may be used to control a typewriter to print words. In Figs. 6 and 7 such a keyboard is shown incorporated in a remote control unit for a typewriter. The keys close contacts which are electrically connected to solenoids such as solenoids If and Cc, Fig. 8, for operating key levers of ordinary typing mechanism. The showing in Fig. 8 is a modification wherein the keys are assembled under the same cover as the typing mechanism. The remote control unit in Figs. 6 and 7 will be described first because the parts are shown larger and in greater detail in these views.

The unit is built upon a base plate 56 over which there is secured a cover 57. The keyboard frame comprises a top plate 58 and a bottom plate 59 held together by four spacing posts 60. The bottom plate 59 is supported above the base plate 56 by a series of six studs 61 which fasten the keyboard to the base.

The two keyboard plates 58 and 59 are slotted

to guide the eight columns of character keystems such as stems 5a, 5b and 5c and also guide six similar keystems depending from the control bars at the center of the keyboard. Taking keystem 5c for an example it is noted that a coil spring 62 around its lower end presses between the bottom plate 59 and shoulders on the keystem to urge the key up to a normal raised position. An extension 63 on the lower part of the keystem

- 5 acts as an upper limiting stop. The slots 64 in the lower plate are long enough so that the lower part of the keystems may pass therethrough when assembling the keyboard, but after all the keys are in the frame they are pushed to the 10 rear of the slots by a locking plate 65 which abuts against the front edge of the keystems to position them with extensions 63 under a solid part of plate 59. Locking plate 65 is secured to plate 59 by nuts 66 on threaded ends of posts 60. 15 A shoulder 67 is cut in the edge of the keystem to abut against the top of plate 58 and limit the downward movement of the key.

The keys associated with the middle, ring and little fingers are provided with locking means 20 for holding them in a depressed position because they do not cause immediate operation as the index finger keys do, but must await sequential timing control in the order named. The keys of the middle and ring fingers operate a linkage to release the timing devices and at the same time lock all keys except the index finger keys in normal or depressed positions. The index finger keys 21', 22', 23', 2a', 2b' and 2c' (Fig. 5) may be operated alone to print one character without being locked and without operating the timer. The special control bars 17", 33", 34", 35, 36 and 37 may also operate without being locked down and without releasing the timer. However, when a word, part of a word, or a plurality of characters are to be printed in one operation, then either of the middle or ring finger keys 24', 25', 26', 2d', 2e', 2f' and 27', 28', 29', 2g', 2h', 2i' are operated to release the timing and locking control linkage as shown in Fig. 13.

- 45 Referring to Fig. 13, it is noted that all three keystems 5a, 5b and 5c of the right hand ring finger keys 2g', 2h' and 2i' are provided with shoulders 68 projecting over the top of lugs 69 extending from one side of a horizontal timer release link 70 which is pivoted at the front end on a stud 71 on a bell crank 72 and articulated at the rear on a stud 73 on a bell crank 74. The middle lug 69 extends at 75 around the side of keystem 5b to prevent link 70 from swaying on pivots 71 and 73 and getting out of the path of shoulders 68. A spring 76 urges the link 70 normally up against the underside of shoulders 68 and also serves to restore the entire linkage on bell cranks 72 and 74 when depressed keys are unlocked. Bell crank 72 is loosely pivoted on a short shaft 82 which is supported on a pair of brackets 83 riveted to plate 59, and bell crank 74 is attached to a long shaft 84 turning in a pair of brackets 85 secured to bottom plate 65 59.

The upper ends of bell cranks 72 and 74 are pivoted at 77 and 78 to a horizontal key locking link 79 extending between the cranks. Projecting from the upper edge of link 79 are three offset extensions 80 bent at an angle to cooperate with either the upper or lower sides of points 81 formed on the keystems. If a key is depressed when link 79 moves to the right, then extension 80 cooperates with the upper face of point 81 to hold the key locked down, but if the keystem

is in normal position when link 79 is moved to the right by another key, then extension 80 passes under the lower face of point 81 to prevent subsequent depression of the keystem.

Whenever one or a pair of the three keys are operated, shoulders 68 press down on timer link 70, and as the link is lowered, bell cranks 72 and 74 are rocked in a clockwise direction, carrying locking link 79 to the right to lock down any depressed keys and hold up any keys that are not depressed. Parts 70, 72, 74 and 79 comprise a linkage parallelogram wherein movement of one part induces movement of the other parts.

There are four columns of parts such as shown in Fig. 13, two columns being under the middle and ring fingers of the right hand, Fig. 7, and the other two columns being operated by the middle and ring fingers of the left hand. Shaft 84 is long enough to extend across both the right and left hand groups of keys. Two shafts such as 20 shaft 82 are provided, one under the front of the right group of keys and the other beneath the left group of keys.

The little finger keys are also locked when shaft 84 is rocked by operation of any of the 25 middle or ring finger keys. This is done by means of a plain crank 74', Fig. 6, fastened to shaft 84, and carrying a locking link 79' pivoted thereon at 78'. The front end of link 79' is pivoted at 77' on a crank 72' loosely pivoted on shaft 82. Link 30 79' is formed with three extensions 80 adapted to move under or over the points 81 on the three keys. Although the link 79' and the connections thereto are shown in Fig. 6 as associated only with the keys operated by the little finger 35 of the right hand, it may be pointed out that there is provided a similar set of connections at the left end of shaft 84, Fig. 7, for cooperation with the little finger keys of the left hand.

It may be noted that the six index finger key- 40 stems and the six control bars are not locked, nor do they operate a timer release link, these keystems being free from any association with control parts such as links 70 and 79 because the contacts these keys operate are effective im- 45 mediately and the setting thereof need not be held.

As seen in Fig. 6, each column of three related 50 keystems 5a, 5b and 5c cooperates with ten contacts to open and close them to establish selective circuits for controlling typing. It is explained more fully hereinafter how two of such sets of 55 ten contacts operated by two similar fingers of both hands, cooperate to select a certain one of 35 characters on one shift or a certain character of 35 others on the other type shift.

The contacts are suspended under and attached to top plate 58 by screws 86 and are separated from the plate and from each other by insulation spacers 87. Certain of the contacts are operated directly by a single keystem while others rely on the depression of a combination of two keys for operation. The contacts for one column of keys are arranged in three groups, two of the groups being placed on the left side of the bank of keys and the other group placed adjacent the right side of the keys as seen in Fig. 7. Pins project from the sides of the keystems and cooperate with the flexible blades of the contacts to move them, or to allow them to move, to open or close 65 the contact points.

When key 2f' is depressed, a pin 41 on the keystem 5a cooperates with the top blade of contacts 4aR to close these contacts. At the same time, as pin 41 moves down it releases the lower

blade of contact 4fR which is then free to open. In the same way, a pin 43 on keystem 5b operates to close contacts 4cR and open contacts 4gR when the key is depressed; and keystem 5c carries a pin 46 which closes contacts 4eR and opens contacts 4hR.

Keystem 5a carries another pin 40 upon which rests the center blade of a related pair of contacts 4bR and 4bR'. This center blade not only rests on pin 40, but it also overlies a pin 42 on keystem 5b so that both keys 2j' and 2k' must be depressed before the center blade may lower to open contacts 4bR and close contacts 4bR'.

In the same fashion, pins 44 and 45 on keystems 5b and 5c, respectively, both support the center blade of contacts 4dR and 4dR', so that both keys 2k' and 2l' must be depressed together before contacts 4dR are opened and contacts 4dR' are closed.

The eight sets of contacts cooperating with the eight columns of keys are similar in construction and operation, so that the foregoing description referring to the contacts associated with the keys of the little finger of the right hand, applies as well to the other seven sets of contacts. The sets of contacts are distinguished from each other by the ending reference letters, R and L denoting right and left hand operation, and the beginning numbers 1, 2, 3 and 4 denoting operation by the index, middle, ring and little fingers, respectively.

Each of the six control bars at the center of the keyboard has associated therewith a separate pair of contacts which are operated individually. When shift bar 33' (Fig. 7) is depressed a pin 50 thereon closes contacts SHC. Space bar 17' lowers pin 51 to close contacts SPC. Contacts BSC are closed by a pin 53 on the back space bar 35. Carriage return bar 36 controls the closing of contacts CRC through a pin 54, and a pin 55 on the stem of the tabulate bar 31 closes contacts TBC. Contacts SLC are closed by a pin 52 on the shift lock bar 34'. The keystem of this shift lock bar is notched at 88, Fig. 6, to engage with a cover plate 89 and lock it depressed to hold contact SLC closed as long as the operator desires shift control. Plate 89 is suitably supported above top plate 58 and covers the space between keys under an opening 90 in case 57 through which the key tops protrude.

When selected combinations of contacts have been operated they are held in operated position by the cooperation of locking links 19 with the keysystems. They are held thus until contact timing devices have made a serial distribution of impulses through the contacts, starting with the index finger contacts, next the middle finger contacts, etc.

The impulse timing device comprises a series of cam disks 1T, 2T, 3T, 4T, 2Ta, 2Tb, 2Tc, 2Td and AT (Fig. 7) made of insulation material and mounted on a shaft 91 which is supported by bearing brackets 92 fixed to base 56. This shaft 91 is driven through a clutch 93 which is selectively connected to a shaft 94 supported on bearing block 95 and driven by a motor M through a speed reduction gearing unit 96.

The timer clutch 93 is released to connect the constantly running shaft 94 with the timer shaft 91 every time more than one character is to be printed by one stroke of the hands; i. e., whenever any of the middle or ring fingers are operated to depress a link 70, Fig. 13, and rock shaft 84 in a clockwise direction. Attached to shaft

84, Fig. 6, is an arm 97 to the end of which there is loosely pivoted an escapement link 98. This link is guided in a slot cut in an extension 99 on a bracket 100 fastened to base 56. Extending from link 98 is a tab 101 which normally underlies a lug 102 on clutch release disk 103 to prevent the clutch from operating. A spring 104 between link 98 and bracket 100 tends to hold the link in normal position. However, as soon as one of the middle or ring finger keys is operated, shaft 84 is rocked, and link 98 is drawn to the left, moving tab 101 away from lug 102 which is then free to swing down in a counter-clockwise direction to connect the clutch.

The clutch parts are shown in detail in Figs. 9, 10, 11 and 12. In Fig. 9 it is noted that two lugs 102 form part of disk 103 which is secured to another disk 105 by a pair of spacing rivets 106. Disk 105 is fastened to a hub 107 that is fixed to shaft 91. Disks 103 and 105, Fig. 12, are formed with three coinciding tapered slots 108 curving around the periphery of shaft 94. In these slots there are placed three hardened cylinders 109 which may rotate freely in the large ends of slots 108, or be wedged between shaft 94 and the small ends of slots 108 to create a driving connection between shaft 94 and disk 103 which is connected to shaft 91 through hub 107.

The three cylinders 109 are urged into a wedging position by a spring plate 110, Fig. 10, which is loosely pivoted on shaft 94 in the space between disks 103 and 105. A spring 111 connected to plate 110 tends to turn it in a counterclockwise direction so that three inwardly projecting feet 112 thereon, bear against the sides of cylinders 109 and press them towards the narrow ends of slots 108. The cylinders are normally prevented from being effective because the disk 103 is held positively by tab 101, Fig. 6, from movement in a clockwise direction (Fig. 12). However, as soon as tab 101 moves away from lug 102, plate 110 shifts the cylinders into driving position in the slots, and timer shaft 91 is driven by shaft 94 through the clutch parts.

The ends of cylinders 109, Fig. 9, are confined between hub 107 and a cover plate 113 fastened against disk 103 after the cylinders are assembled therein.

The two lugs 102, placed opposite each other on disk 103 adapt the timer parts for a movement of 180° per operating cycle. As tab 101 moves out of the path of one lug 102, another tab 114 on escapement link 98 moves into the path of the other lug 102 to hold the clutch if the keys fail to restore, or if someone should hold the keys down at the end of an operation when they should be restored. When the keys are properly restored, shaft 84 swings link 98 back to normal position and a clutch lug 102 is brought against the top of tab 101.

Depressed keys are released near the end of the timer operation by one of a pair of cam faces 115 on hub 107. These cams strike against the upper end 116, Fig. 6, of a latch lever 117 pivoted at 118 on the bracket 100. A spring 119 pulls the lever in a clockwise direction so that a tab 120 rests on the outer edge of a notched locking arm 121 fastened to shaft 84. When shaft 84 is rocked in a clockwise direction by the depression of any keys, arm 121 swings down and tab 120 is lifted against a stepped shoulder 122 on the arm. Thus arm 121 is locked from swinging back in a counterclockwise direction and shaft 84 is prevented from being restored as urged by springs 126 and 104, and the depressed keys

are held down by links 78 and extensions 80 until near the end of the 180° arc of movement of the timer shaft 91 when one of the cam faces 115 strikes end 116 of lever 117 and rocks it in a 5 counterclockwise direction to move tab 120 away from arm 121. The arm and shaft 84 are then free to rock back in a counterclockwise direction carrying links 79 along therewith to release the keys. Shaft 84 serves two purposes, to control 10 the locking and releasing of the keys, and to govern the escapement of the clutch. At the same time that released shaft 84 rocks in a counterclockwise direction to free the keys, attached escapement link 98 moves to the right to take tab 114 out of the path of lug 102 and bring tab 11 101 under the tab to stop the clutch in the normal released position.

An interlock is provided between a starting switch and the character keys to prevent the 20 keys from being latched down when the machine is not operating, and then causing typing as soon as the switch is thrown on. An operating knob 125 of a toggle switch is confined between two offset extensions 126 of a switch lever 127 pivoted at 128 on a bracket under the top keyboard plate 58. Another extension 129 is bent on the lower end of the lever which is out of the path of latch lever 117 when the switch is "on" as shown in Fig. 6. However as soon as the switch 25 is moved to the dotted line "off" position, extension 129 is moved over to abut against the top of a raised portion 130 on lever 117 and prevent that lever from cooperating with latch arm 121 when keys are operated. Therefore, when keys are operated while the operating current is disconnected, such keys are not locked down, because if they were locked down they would cause immediate undesirable typing operation as soon as the switch is thrown on.

The timer cam disks 1T, 2T, etc., on shaft 91 are turned in a counterclockwise direction (Fig. 6) to cooperate with rollers 131 on the ends of flexible lower operating blades 132 of sets of contact blades separated by insulation blocks 133 and mounted by screws 134 on an upturned flange 135 of the base 56. The disks 1T, 2T, 3T and 4T are formed with cam extensions which are effective in the order named to operate associated timing contacts in sequential order. There is provided an operating blade 132 (Fig. 7) and a set of contacts for each of the nine timer disks. 50

As shown in Fig. 6 it is apparent that the timer cam 1T, relating to the index finger contacts, is normally positioned with a raised portion under roller 131 so that blade 132 is raised to close contacts 1R and 1L simultaneously by means of motion communicating insulation bars 136 and 55 137. When roller 131 is lowered by the passing of the cam face, both contacts open at the same time.

The three other sets of contacts associated with timer cams 2T, 3T and 4T are constructed the same as the 1R—1L contacts, the only difference being in their time of operation which is brought about by the placement of the timer cam shapes which take effect after cam 1T in the cycle to close the contacts in succession.

The contacts associated with timer disks 2Ta, 2Tb, 2Tc and 2Td are of a slightly different form. 70 In these sets of contacts, upper contacts 2n, 2p, 2s and 2u are normally open and lower contacts 2m, 2o, 2q and 2v are normally closed. These contact positions are all reversed at the same time, at the same instant that the cam face on timer 2T is effective. This is true because all

these contacts relate to the selective operation of special characters by the middle fingers which are effective second in time of operation in the printing cycle. In order to close the upper contacts and open the lower contacts of these special banks, motion communicating bars 138 and 139 are placed between the lower operating blade and the contact blades. These contacts are shown diagrammatically at the center of Fig. 14 in reference to which they are described more fully hereinafter. 10

Timer disk AT (Fig. 7) is of the same form as disk 1T and has cooperating therewith a single contact AC which is normally closed. This contact is opened as soon as typing is started to prevent the special operations of shift, space, back 15 space, etc., from taking place at the same time.

The modified form of keyboard and timing controls shown in Fig. 8 is of the same general construction and operation as the remote control unit already described with reference to Figs. 6 20 and 7. The few differences brought about by the rearrangement of parts in Fig. 8 are about to be pointed out.

The lower keyboard plate 59' is not supported 25 directly on the base but it is secured to side frames 140 by screws passing through depending lugs 141 on the plate.

The clutch escapement release member is in the form of a bell crank 98' pivoted at 142 on 30 a bracket 100'. The upper arm of the bell crank has a pin and slot connection 143 with an arm 97' fastened to the release shaft 84. Clockwise rocking of shaft 84 serves to turn crank 98' in a counterclockwise direction and push a tab 101' 35 thereon out of the path of the clutch lug 102 to allow the clutch to turn.

Near the end of a cycle, a cam face 115 on the clutch strikes the end of a latch lever 117' which is pivoted at 118' on a bracket 144 fastened 40 underneath keyboard plate 59'. This lever 117' is provided to lock shaft 84 in rocked position and hold depressed keys down until a cycle is completed. A spring 119' holds the latch against a shouldered arm on shaft 84. The upper end of lever 117' projects into the path of the lug 129 on the switch lever 127 so that when the switch is thrown off, the latch lever 117' is obstructed from counterclockwise movement and thus disabled from locking depressed keys. 45

The printing devices about to be described are 50 operated by solenoids which may be energized as controlled by keyboard contacts and timer contacts directly associated with the printer as shown in Fig. 8, or by impulses from a distance, said impulses being initiated by a remote control keyboard such as that illustrated in Figs. 6 and 7.

A plurality of solenoids such as solenoids Ii and Cc (Fig. 8) are arranged in two rows in staggered formation on a bar 150 extending across 60 the machine and fastened on side frames 140. Sliding within each solenoid is a plunger 151 pivoted at 152 near its upper end on an operating arm 153 fulcrumed in a vertical rod 154. The end of arm 153 is pivotally connected to a link 155 with a pin and slot connection 156 to a key lever 157 of a machine known as an "Electromatic" typewriter. Although an illustration is made in connection with this machine it is apparent that the keyboard devices disclosed are adapted to control other forms of typewriters and recording machines. 65

The links 155 of the various key levers are all 70 in one row, but the arms 153 connected there- 75

with are attached alternately, first from one row of solenoids and next from the other row of solenoids.

The type lever mechanism operated by lever 157 is described in detail in Patents 1,945,847 and 1,873,512. The type bars 160 are operated by a constantly turning power driven roller 161 with which cams 162 are adapted to cooperate to actuate the type bars. The cams 162 are pivoted on bell crank levers 163 operatively connected with the type bars by means of links 164 which operate levers 165 which in turn are connected with the type bars by means of links 166. The cams 162 are normally out of engagement with the roller 161 but resiliently urged into engagement therewith by spring pressed arms 167 which engage projections 168 on the cams. The cams 162 also have laterally projecting lugs 169 which engage stops 170 on levers 171 pivoted on the bell cranks to hold the cams out of engagement with the roller against the tension of arms 167. The upper ends of levers 171 are provided with offsets 173 which are engaged by the bifurcated ends of arms on key levers 157. When a lever 157 is pulled down by a solenoid, it swings the lever 171 and moves the stop 170 out of the path of the lug on the cam and permits the arm 167 to turn the cam into engagement with the power driven roller 161 to be turned thereby and thus, due to the eccentricity of the cam, the bell crank 163 is rocked and the type bar 160 is thrown against the record sheet and platen 172 to leave a printed impression.

Solenoids are provided not only to control the printing of letters, numbers and special characters, but also to control the typewriter operating functions. Referring to the wiring diagram in Fig. 14 it is noted that contacts SHC, SPC, SLC, BSC, CRC and TBC, previously pointed out as closed by the shift, space, shift lock, back space, carriage return and tabulate bars, respectively, are wired in parallel, each connected to a related one of six control solenoids SH, SP, SL, BS, CR and TB. All six pairs of solenoids and contacts are connected in series with the normally closed timer contacts AC making current through lines 175 and 176 available immediately upon the closing of any of the special contacts. The typewriter controls which are operated by the solenoids are set forth in detail in patents that are about to be pointed out. The solenoids SH and SL actuate a shift mechanism for selecting upper case type as set forth in Patent 1,945,097. The spacing or carriage escapement mechanism operated by solenoid SP is disclosed in detail in Patent 1,873,512. Back space control mechanism disclosed in Patent 1,873,553 may be operated selectively by solenoid BS. Carriage return operation is exercised by solenoid CR when it pulls down the operating lever of the mechanism detailed in Patents 1,753,450 and 1,955,614. Solenoid TB initiates tabulating movement of the carriage by means of mechanism such as that revealed in Patent 1,935,436.

Closure of the main power switch PS, Fig. 14 and machine switch 125, connects the main lines 175 and 176 to the source of electric current. Switch 125 is the one described hereinbefore with reference to the keyboard as having interlocking control over the key locking means so that no keys are locked down while this switch is off. However, as shown in Fig. 14 and the other figures, the switch is on and the keys are latched down for serial operation.

The timer operating motor M is connected

across lines 175 and 176 so that it is in constant operation after switches PS and 125 are closed.

Two lines of solenoids are shown at the middle of the wiring diagram. These solenoids are connected with key levers 157 (Fig. 8) of the typewriter to control type bars 160 to print letters, capitals, numbers, punctuation marks and special signs. Each solenoid is designated with the characters which the associated type bar is adapted to print. The first character of each designation is the upper case or shift selected figure, while the second character is the ordinary lower case unshifted character. For example, the solenoid 9! when energized ordinarily controls the printing of an exclamation mark, but if the shift bar 33' is depressed when this solenoid is energized, then a 9 is printed.

As indicated by the solenoid designations, certain of the numeral type are duplicated. This is so because associated with these numerals 1, 2, 3, 4, 5, 6 and 7 are the infrequent special marks : () \$ & / and % which may be selected instead of the more frequently used marks , - ' ' and ;. These infrequent mark solenoids 1:, 2(, 3), 4\$, 5&, 6/ and 7% are connected to timer contacts 2u, 2s, 2p and 2n which are closed only at the second instant in the cycle, which is the time that the middle finger contacts are effective through timer contacts 2R, so that these infrequent marks are selected only by the middle fingers as pointed out hereinbefore with reference to the chart showing the key combinations related to the infrequent marks. Even though these signs are printed as a second operation in the cycle, no back space operation is required because the index finger keys may be left undisturbed when printing the infrequent marks.

All other solenoids, except the seven mentioned, are wired between the main lines 175 and 176 in series with all eight sets of the keyboard finger contacts. Any solenoid may be energized by any of the four pairs of sets of keyboard contacts. The 35 ordinary solenoids are wired so that each may be selected by one of the 35 different combinations of contact closures brought about by the depression of combinations of the six related keys. The index finger contacts are effective first because these contacts are wired in series with the normally closed timer contacts 1R, 1L associated with timer cam 1T. The other middle, ring and little finger contacts are wired in series with timers 2R, 2L; 3R, 3L and 4R, 4L and are made effective in that order by timer cams 2T, 3T and 4T. Examples may be taken to point out the path of the current through the contacts, solenoids and wiring.

The letter e is selected by depressing key 2b' (Fig. 5) which serves to close contacts 1cR (Fig. 14) and open contacts 1gR. The print controlling circuit may be traced from line 176 through contacts 1R, normally closed contacts 1dR, wire 180, normally closed contacts 1bR, wire 181, contacts 1cR, wire 182, wire 183, solenoid Ee, wires 184, 185, 186 and 187, normally closed contacts 1hL, 1gL and 1fL, wire 188 and through contacts 1L to line 175. The energized solenoid Ee then pulls down the key lever to throw the type bar against the record sheet to print the letter e.

The letter m is selected by depressing the key combinations 22', 23' and 2a', 2b' which serve to close contacts 1cL, 1eL, 1dL', 1aR, 1cR, 1bR' and open contacts 1gL, 1hL, 1dL, 1fR, 1gR and 1bR. The circuit established thereby may be followed from line 176 through contacts 1R, normally closed contacts 1dR, wire 180, contacts 75

$1bR'$, wires 189, 190 and 191, solenoid Mm, wires 192 and 193, closed contacts $1dL'$, wire 188 and contacts $1L$ to line 175.

If it had been desired to capitalize the letter m just selected, the shift bar 33' would have been depressed before the character keys and held depressed with the character keys until M is printed. When this M is at the beginning of the first word of a sentence, the remainder of the word may be printed directly thereafter by releasing the shift bar 33' and depressing combinations of middle, ring and little finger keys. The described form of operation is one whereby the shift bar 33' acts as a 1st capital control.

15 For the capitalization of an entire word or sentence, bar 33' may be held down or the shift lock bar 34' may be latched down to free the thumbs for other control operations.

The shift lock bar 34' instead of operating through solenoid SL and thus being dependent on timer AT, may be considered to be the usual mechanically connected shift lock key provided in the typewriter. This ordinary mechanical construction may be used on machines for typing 25 work with frequent lines of upper case letters and numerals.

The printing of a period may be selected by depressing key 21' to close contacts $1aL$ and open contacts $1L$. The circuit may be followed from line 176 through timer contacts $1R$, normally closed contacts $1fR$, $1gR$ and $1hR$, wires 194, 195, contacts $2m$ closed at the 1st, 3rd and 4th instant of the printing cycle, wire 186, solenoid 2., wires 197, 198 and 199, closed contacts $1aL$, normally closed contacts $1bL$ and $1dL$, wire 188, timer contacts $1L$ and line 175. It may be noted that this is one of the key combinations that selects infrequent marks in the 2nd instant of the printing cycle when set up by the middle fingers. 40 That is why the period circuit goes through contacts $2m$ which may be opened and contacts $2n$ closed at the 2nd instant to select the bracket mark (instead of a period. In other words, depression of keys 21', 27' or 30' (Fig. 5) selects 45 the printing of a period, while depression of the corresponding key 24' in the middle finger row selects the printing of a bracket mark. The circuit set up by the depression of key 24' and the closure of contacts $2aL$ may be traced to point out how a (is printed instead of a period. From line 176 the current passes through timer contacts $2R$ closed by cam 2T at the 2nd instant in the cycle, thence through normally closed contacts $2fR$, $2gR$ and $2hR$, wires 200, 201 and 195, contacts $2n$ closed at the 2nd instant by timer cam 2Ta, wire 202, solenoid 2(), wires 197, 198 and 199, contacts $2aL$, $2bL$ and $2dL$, timer contacts $2L$ closed at the 2nd instant by cam 2T, and line 175. In the same manner the other cams 50 2Tb, 2Tc and 2Td switch connections at the 2nd instant to connect one of the six other infrequent mark selection solenoids into the circuit instead of the solenoids controlling the typing of frequently occurring signs and marks. Directly before, and immediately after the 2nd instant in the printing cycle, the timer cams permit contacts $2m$, $2o$, $2q$ and $2v$ to close to make available the frequently used solenoids if the index, ring or little fingers should select such solenoids.

70 An example may be given to illustrate the mode of operation when a plurality of combinations of keys are depressed on the keyboard simultaneously to print a word with one stroke of the hands. To represent the word "pure" the keys 75 $2b'$, $2e'$, $2f'$, $2h'$, $2i'$ and $2k'$, Fig. 5, are depressed

by the fingers of the right hand while the keys 21', 24', 25' and 28' are depressed by the fingers of the left hand. This results in the closure of contacts $1cR$, $2dR'$, $3dR'$, $4cR$, $1aL$, $2bL'$ and $3cL$. Then there follows the initiation of four impulses in rapid succession to control the printing of the four letters p u r e as follows:

The first impulse travels through line 176, normally closed contacts $1R$ and $1dR$, wire 180, contacts $1bR$, wire 181, closed contacts $1cR$, wires 10 182 and 183, solenoid Pp, wires 197, 198 and 199, manipulated contacts $1aL$, normally closed contacts $1bL$ and $1dL$, wire 188, contacts $1L$ and line 175. Immediately after the letter p is printed, contacts $1R$ and $1L$ open and contacts $2R$, $2L$ 15 close to initiate the printing of the second letter.

The second impulse passes from line 176 through contacts $2R$, closed contacts $2dR'$, wires 205, 206 and 207, solenoid Uu, wires 208, 209, 210 and 211, manipulated contacts $2bL'$, normally 20 closed contacts $2dL$ and contacts $2L$ to line 175. Thus control is exercised to print u after which contacts $2R$ and $2L$ open, and contacts $3R$, $3L$ close to print the third letter.

Starting through line 176 and contacts $3R$ the 25 third impulse passes through manipulated contacts $3dR'$, wires 212, 206 and 207, solenoid Rr, wires 213, 214, 215 and 216, manipulated contacts $3cL$, normally closed contacts $3bL$ and $3dL$ and contacts $3L$ to line 175. After the r is printed, 30 contacts $3R$, $3L$ open and contacts $4R$, $4L$ close to control the printing of the fourth letter.

The fourth impulse is directed from line 176, through contacts $4R$, normally closed contacts $4dR$ and $4bR$, manipulated contacts $4cR$, wires 35 182 and 183, solenoid Ee, wires 184 and 185, normally closed contacts $4hL$, $4gL$ and $4fL$, contacts $4L$ and line 175. This last circuit controls the printing of the last letter e of the word "pure". Directly thereafter the contacts $4R$, $4L$ are 40 opened and the contacts $1R$, $1L$ are closed as the timer clutch is disconnected and held in normal position in preparation for a new printing cycle.

Contacts AC open after the first part of a printing cycle to prevent the operation of any 45 of the controls by solenoids SH, SP, SL, BS, CR and TB while successive printing is taking place.

While the illustrative machines are fully shown and described in pointing out the fundamental novel features of the invention, it will be understood that various omissions, substitutions and changes in the form and details of the machines and their operation, may be made by those skilled in the art without departing from the spirit of the invention. It is the intention, therefore, to 55 be limited only as indicated by the scope of the following claims.

What is claimed is as follows:

1. In a recording machine, two parallel columns of keys, the keys of one column being located for 60 operation in combination by one finger of the right hand, and the keys of the other column being located for operation in combination by a finger of the left hand, both fingers serving to set up one of a plurality of combinations, electrical contacts associated with the keys and closed and opened in accordance with the combination of keys operated, a set of type with each type related to a different combination of the keys, and electrical devices under control of said contacts for printing from the type selected by the operated combination of keys.

2. In a recording machine, a set of six keys arranged in two columns for operation singly and in combination by a pair of fingers, two groups 75

- of electrical contacts, one for each column of keys, with five normally open contacts and five normally closed contacts in each group, means under control of the keys for reversing the condition of the contacts, a set of typebars, a solenoid for operating each typebar to cause printing, and wiring connections from said contacts to said solenoids so arranged that a different solenoid is energized for each different combination of keys operated.
3. In a recording machine, a plurality of sets of keys, the keys of each set being arranged in two parallel columns for operation in combination by two similar fingers of different hands, a set of type, one type for each key combination, electrical type operating means including connections between each of said sets of keys and said set of type, and means cooperating with said connections to make the sets of keys control said operating means seriatim.
4. In a recording machine, a printing means comprising a plurality of type, sets of keys, the keys of each set being operable in combination to select type, there being a separate set of keys for the index, middle, ring and little fingers, and means under control of said keys for operating to print a record from the selected type, said operating means being controlled distally, the index finger keys selecting the first type to print and the middle, ring and little finger keys controlling subsequent printing in the order mentioned.
5. In a recording machine, a plurality of type, a set of type selecting keys comprising two groups of keys, means under control of one group of keys operated singly or in combination by a finger of one hand to select a group of type, means under control of the other group of keys operated singly or in combination by a finger of the other hand to select one of said selected group of type, and means for making a printed impression of the selected type.
6. In a recording machine, a plurality of type, solenoids, one for each type for conditioning the type for printing, a set of type selecting keys arranged in two columns, a source of electrical energy, electrical contacts connected to different groups of solenoids and selectively closed by operation of the keys of one column, other electrical contacts connected to different solenoids in the groups and selectively closed by operation of the keys of the other column, and means for making a printed impression of the selected type.
7. In a recording machine, a plurality of type, electrical devices for conditioning the individual type for printing, sets of type selecting keys arranged in pairs of columns, a source of electrical energy, pairs of groups of electrical contacts, each group associated with a column of keys, the contacts of one contact group of each pair being connected to different groups of said conditioning devices and selectively closed by the keys of one column, the contacts of the related contact group of the same pair being connected to different conditioning devices of the selected device group and selectively closed by the keys of the related column, means for making the control from the different sets of keys effective seriatim, and means for taking printed impressions of the selected types.
8. In a recording machine, a set of character type, a plurality of special character type, sets of keys, each set operable in combinations to select a type for printing control, alternate connections between certain of said character type and said special character type, means for changing said connections to make possible the selection of said special character type at a certain time, means for timing the effectiveness of said sets of keys, one of said sets being effective at said certain time the connections are changed to select special type, and means for printing a record of said selected character type and other character type.
9. In a typewriter with a set of character type, sets of type selection keys, each set operable in combination to select a type, a plurality of sets operated simultaneously, means for operating the selected type to print, timing devices to control the sequence in which the sets of keys are made effective, driving means for said devices, a clutch between said devices and said driving means, and an escapement release member controlled by the keys for connecting said clutch, said member disconnecting said clutch after one cycle of operation regardless of the position of the keys in operated or released condition.
10. In a typewriter with a set of character type, sets of type selection keys, the keys of each set being depressed in combination to select a type, means for operating the selected type to print a record, means for locking the keys in depressed or released position during printing, a driving means for said operating means, a clutch between said operating and driving means, means for connecting said clutch, and means under control of the keys for operating said key locking means and said clutch connecting means.
11. In a power operated typewriter, a driving means, a control switch for said driving means, keys for controlling typing, means for locking said keys in an operated position, and means under control of said switch for rendering ineffective said locking means when said switch is moved to the "off" position.
12. In a recording machine, a set of six keys arranged in two columns, three keys in a column, the keys of each column being operable singly or in pairs by a finger, a plurality of type bars, means under control of said six keys for selecting one of said bars according to the combination of one, two, three or four keys operated, and means for recording an impression of the selected type-bar on a record sheet.
13. In a recording machine, a plurality of sets of keys, the keys of each set being arranged in two parallel columns with a plurality of keys in each column, the keys of a column being operable singly or in combination with the keys of the other related column, the keys of one column being operated by a digit of the right hand, and the keys of the other related column being operated by a similar digit of the left hand, a recording means with a plurality of type each type relating to a combination of the keys, and means under control of operated keys for selectively impressing certain type against a record sheet to print a plurality of letters of a word.
14. In a recording machine, four sets of keys, each set arranged in two columns with three keys in each column, four columns operated by the fingers of the right hand and four other columns operated by the fingers of the left hand, the three keys of a column being operable by one finger singly or two at a time in combination with the keys of a related column operated by a similar finger of the other hand, printing elements, means under control of each combination of operated keys for selecting one of said elements for recording operation, and means for taking an impression of the record sheet.

impression of the selected elements on a record sheet.

- 5 15. In a recording machine, a plurality of groups of keys operated by pairs of digits, the 5 keys of each group being operable singly or in combination to represent a character, a printing means with type representing characters, and means under control of the keys for operating the printing means to print a plurality of characters, the left to right order of the characters printed on a record sheet being controlled by the groups of keys under control of the pairs of index, middle, ring and little fingers in the order mentioned.
- 10 16. In a recording machine, a set of six keys designated 21, 22, 23, 2a, 2b and 2c arranged in two columns as follows:

21 2a
22 2b
23 2c

20 the keys of each column being operable singly or in adjacent pairs by a finger, and being jointly operable with keys of the other column, 25 said six keys being operable in thirty-five combinations, printing devices with a set of alphabet type and a plurality of punctuation type, and means for selectively operating the type to print a record according to the following key combination selections:

e	2b	Period	21
t	22	c	23
o	22-2b	b	22-2a
35 a	2a, 2b	g	22-2c
h	2b, 2c	p	21-2b
n	21, 22	v	23-2b
i	22, 23	Dash	21, 22-2a
s	22-2a, 2b	Quotation marks	21, 22-2c
40 r	22-2b, 2c	k	22, 23-2a
d	21, 22-2b	Apostrophe	22, 23-2c
l	22, 23-2b	Underline	21-2a, 2b
f	21, 22-2a, 2b	Semicolon	23-2a, 2b
45 w	22, 23-2b, 2c	Question mark	21-2b, 2c
u	21, 22-2b, 2c	Exclamation	23-2b, 2c
m	22, 23-2a, 2b	x	21-2a
y	2a	j	23-2c
50	Comma 2c	q	21-2c
		z	23-2a

17. A recording machine as in claim 16 with sets of upper case alphabet type and numeral type and a shifting means between the keys and type to select the upper case and numeral type to print a record according to the following key combination selections:

E	2b	2	21
T	22	C	23
O	22-2b	B	22-2a
A	2a, 2b	G	22-2c
H	2b, 2c	P	21-2b
N	21, 22	V	23-2b
I	22, 23	3	21, 22-2a
S	22-2a, 2b	4	21, 22-2c
R	22-2b, 2c	K	22, 23-2a
D	21, 22-2b	5	22, 23-2c
L	22, 23-2b	6	21-2a, 2b
F	21, 22-2a, 2b	7	23-2a, 2b
W	22, 23-2b, 2c	8	21-2b, 2c
U	21, 22-2b, 2c	9	23-2b, 2c
M	22, 23-2a, 2b	X	21-2a
Y	2a	J	23-2c
I	2c	Q	21-2c
		Z	23-2a

18. In a power driven typewriter, four sets of keys, each set arranged in two columns with three keys in each column, four columns operated by the fingers of the right hand and the other four columns operated by the fingers of the left hand, the three keys of a column being operable by one finger singly or two at a time in combination with the keys of a related column operated by a similar finger of the other hand, a set of character type bars, power operated means for operating said bars to type on a record sheet, means including solenoids for each of said bars for bringing selected bars under control of said operating means, a source of electrical energy, four sets of electrical contacts 15 the contacts of each set being opened and closed by two cooperating columns of keys to form current paths between said source and any of said solenoids to which the contacts are wired, four pairs of timer contacts, each pair of which 20 is connected between said source and the key contacts of two related columns of keys, a timer driving means, four timer cams designed to close said timer contacts in succession, first the pair associated with the index finger keys and then 25 the contacts of the middle, ring and little finger keys in the order named, a clutch between said driving means and said cams, and means for connecting said clutch under control of the middle and ring finger keys. 30

19. In a recording machine, a set of type, sets of keys operable by pairs of similar fingers simultaneously in combinations to select the type for printing, timing devices between said keys and said type to make the sets of keys effective 35 in succession, the set of keys operated by the index fingers being effective immediately, means under control of said keys for calling said devices into operation only when other sets of keys are operated in addition to the index finger keys, 40 and means for printing a record under control of the selected type.

20. In a recording machine, three lateral rows of keys arranged according to the natural positions of finger tips, the keys comprising a 45 plurality of sets with two related columns of keys in each set, related columns of keys being equally spaced from the center to the left and right, and positioned under similar fingers of opposite hands, said keys being aligned longitudinally and closely spaced in the columns so that a combination of keys in two related columns can be depressed by each pair of fingers to select a single letter, and all fingers operated simultaneously to select a plurality of letters of 55 a word, a recording means with a plurality of type, each type relating to a combination of the keys, and means under control of operated keys for selectively impressing certain of the type against a record sheet to print a plurality of 60 letters of a word.

21. In a recording machine, five groups of keys, one group for each digit, said keys of a group being operable singly or in combination by a digit, a printing means comprising a plurality of type, a different type for each combination of keys, means under control of the combinations of operated keys for selecting certain type, and means under control of said keys for operating to print a record from the selected type, said operating means being controlled distally, the thumb keys selecting the first type to print and the index, middle, ring and little finger keys controlling subsequent printing in the order mentioned. 70

22. In a recording machine, a plurality of sets of keys, each set arranged in two groups, related groups being equally spaced from the center to the left and right, and positioned under similar fingers of opposite hands, said keys of the groups being positioned adjacent each other in the groups so that a combination of keys in two related groups can be depressed by each pair of fingers, all fingers being depressed at the same time and each finger operating one or a combination of keys of the associated group, each different combination of a set of keys relating to a letter so that all sets represent a plurality of letters of a word, printing means with type representing the different letters, and means under control of the keys for operating the printing means to print a plurality of letters, the left to right order of the letters printed on a record sheet being controlled distally by the sets of keys.
23. A recording machine comprising three sections of keys, each section including a plurality of keys, a left section adapted to be controlled by the fingers of the left hand, a center section controlled by the thumbs of both hands, and a right section controlled by the fingers of the right hand, the thumbs depressing combinations of keys in the center section to select the first letter of a word, pairs of related groups of finger keys being in the left and right sections, said related groups of finger keys being equally spaced to the left and right of the center section and positioned under similar fingers of the opposite hands, said keys of the groups being positioned adjacent each other in the groups so that a combination of keys in two related groups can be depressed by each pair of fingers to select other letters of the same word simultaneously, letter printing elements, means under control of each combination of depressed keys for selecting one of said elements for recording operation, and means for effecting an impression of all selected elements to print a plurality of letters of a word on a record sheet.
24. In a recording machine, a set of six keys designated a'' , b'' , c'' , $1''$, $2''$, $3''$, arranged in two columns as follows:

a''	$1''$
b''	$2''$
c''	$3''$

said keys being operable by two fingers, in combinations, singly and in pairs, printing devices with a set of alphabet type and a plurality of punctuation type, record sheet spacing devices,

and means under control of said keys for selectively operating the type and devices according to the following key combination selections:

A	1''	P	3''— b''	5
B	1''— a''	Q	3''— b'' , c''	
C	1''— a'' , b''	R	3''— c''	
D	1''— b''	S	1'', 2''	
E	1''— b'' , c''	T	1'', 2''— a''	
F	1''— c''	U	1'', 2''— a'' , b''	10
G	2''	V	1'', 2''— b''	
H	2''— a''	W	1'', 2''— b'' , c''	
I	2''— a'' , b''	X	1'', 2''— c''	
J	2''— b''	Y	2'', 3''	
K	2''— b'' , c''	Z	2'', 3''— a''	15
L	2''— c''	Space	2'', 3''— a'' , b''	
M	3''	Comma	2'', 3''— b''	
N	3''— a''	Period	2'', 3''— b'' , c''	
O	3''— a'' , b''	Dash	2'', 3''— c''	

25. In a recording machine, a keyboard with five sets of keys, each set comprising two columns of three keys operable singly or in combination by two similar fingers or thumbs of both hands, the thumb columns of keys being arranged side by side at the center of the keyboard and the other columns spaced therefrom to the left and right in accordance with the natural positions of the finger tips, each combination of keys representing a letter, number or punctuation mark, all five combinations being settable simultaneously, and two selection bars placed adjacent the index finger columns of keys, mechanism controlled by said bars to select an additional set of special characters, a recording means with a plurality of type, each type relating to a combination of the keys, and means under control of operated keys for impressing selected type against a record sheet to print thereon a plurality of letters, numbers, marks or characters.

26. A recording machine as in claim 25 with a capital selection bar between the columns of thumb keys and shift mechanism operated thereby to capitalize the letter selected by the combination of keys operated by the thumbs.

27. A recording machine as in claim 25 with a capital selection bar to the left of the thumb keys and shift mechanism operated thereby to capitalize the letter selected by the thumb keys, and a space bar to the right of the thumb keys and sheet spacing mechanism operated when said bar is operated with the thumb keys or alone to select a spacing operation.
